DOOR CLOSING MECHANISM

Heinz Bomm, Ennepetal-Voerde, and Klaus Berghaus, Volmarstein, Germany, assignors to Dorken & Mankel KG., Ennepetal-Voerde, Germany

Filed Mar. 6, 1959, Ser. No. 797,798

Claims priority, application Germany Mar. 13, 1958
7 Claims. (Cl. 16—59)

The present invention relates to an improved door closing device operating from the top of a door and being provided with a hydraulic brake or dashpot.

The instant door closer is of the type comprising a unitary housing adapted to be secured to the top portion of a door frame, an inner casing supported by said unitary housing accommodating a spiral spring circumferentially disposed about a spindle, and a dashpot assembly including a piston and a connecting rod interconnecting said spindle with said piston. The spindle, in turn, is secured to lever means which are fastened to the header of a door frame. A rotating eccentric portion is provided on the free end of the spindle, the connecting rod for the piston of the dashpot being rotatably mounted on this eccentric portion.

In order to obtain the necessary return force for closing a door, door closing mechanisms operating from the upper edge of a door require a certain minimum height which is dependent on the width of the spring disposed in the spring casing. In the instant case, a ratchet means is employed in order to tension the spiral spring, said ratchet means being connected to a door-frame-connecting lever, whereas the end of the spring engages in a locking slot provided in the spring casing. The ratchet wheel can be rotated relative to the spindle in order to adjust the biasing force of the spiral spring.

Door closing devices of the type operating from the top are relatively foolproof and require very little maintenance. However, such top door closers have the disadvantage that they are relatively bulky, particularly with respect to their height and, additionally, they are rather conspicuous and often unattractive. The latter disadvantages are overcome by employing bottom door closers. However, the convenient assemblage, the ready adjustability, the foolproofness in operation and the slight maintenance required of a top door closing device distinguishes the latter favorably from the bottom door closer, so that top door closers will maintain their marketability.

It is, therefore, an important object of the present invention to provide a door closer which is relatively simple in construction and yet highly reliable in operation.

It is another object of the present invention to provide a door closer which is compact and attractive in appearance and wherein the structural height of the casing is decreased.

It is another object of the invention to provide means enabling the horizontal center plane of a dashpot cylinder to be displaced in order to reduce the required height of the housing.

It is another important feature of the invention to provide means for additionally journaling the spindle to ensure greater reliability in operation of the door closing mechanism.

It is a further object of the invention to provide means enabling the width of a spiral return spring to be decreased and, correspondingly, to increase the thickness or strength of a spring band.

Still further objects and the entire scope of applicability of the present invention will become apparent from the detailed description given hereinafter; it should be understood, however, that the detailed description and specific

2

examples, while indicating preferred embodiments of the invention, are given by way of illustration only, since various changes and modifications within the spirit and scope of the invention will become apparent to those skilled in the art from this detailed description.

In the drawings:

FIGURE 1 discloses a longitudinal section of the door closing mechanism according to the present invention;

FIGURE 2 illustrates a top view of the device with the top portion or lid removed;

FIGURE 3 shows in detail the structure of the piston and connecting rod for the dashpot;

FIGURE 4 illustrates in detail the structure of the ratchet wheel for pretensioning a spring member;

FIGURE 5 shows a front view of a mounting plate employed with the door closing mechanism;

FIGURE 6 is a side view of the mounting plate shown in FIGURE 5;

FIGURE 7 is a sectional view of the mounting plate shown in FIGURE 5 taken along the line A—A, with the door closing assembly mounted on a metal door having a narrow door frame partially shown in section;

FIGURE 8 is a fragmentary sectional view of the door closer housing and its associated mounting plate;

FIGURE 9 illustrates a top view of the door closing assembly according to the invention, the top portion of the housing being partially cut open.

Referring in detail to the drawings and, more particularly, to FIGURES 1 and 4, the door closing assembly according to the present invention comprises a unitary external housing 24. Within said external housing 24, there is provided an inner casing for housing a spring 9, said spring being narrower and stronger than heretofore used, and a brake piston 17, which will be more fully explained hereinafter. A bushing 2 is centrally disposed within a cylindrical spring casing 1, said bushing having lateral shoulders 50 which securely bear against the inner stepped recess 51 provided in the floor of the spring casing 1. A rotatable spindle 4, having its axis

parallel to the hinge of the door, is coaxially mounted within the bushing 2 and has one end additionally journalled in a bore 5a provided in a horizontal leg 52 of the internal casing. A ratchet wheel or socket 6 provided with a plurality of circumferentially spaced slots or cutouts 13 is loosely mounted on the opposite end of the bushing 2, said ratchet wheel being provided with a slot or groove 7 for receiving the inner end of a spiral spring 9 disposed in said spring casing 1. The upper portion of the spindle 4 carries a threaded keyway 10 to which is secured a connecting lever 11 by means of a threaded bolt 10a. The head of the lever 11 is provided with a hollow channel 53 supporting a stub shaft 54 onto which a detent element 12 is pivotally mounted, said detent element engaging the slots 13 of the ratchet wheel 6, whereby rotation of the ratchet wheel and subsequent engagement of the detent member with one of the slots 13 effects a predetermined pretensioning of the spiral spring 9. As a result of this arrangement, a coupling pin or bolt, normally provided on the ratchet wheel 6, is no longer necessary, whereby the height of the head of the connecting lever 11 can be decreased by the height of the ratchet means associated therewith.

The connecting lever 11 is secured to the header of a door frame (not shown) in a conventional manner, whereas the external housing 24 is mounted on the top of the door by means of the lateral flange members 14 and 15.

The dashpot assembly includes a cylinder 16, disposed both below and laterally with respect to the spring casing 1, and a piston 17 arranged for reciprocating movement within said cylinder 16. A connecting element or rod 18 has one end connected to the piston 17 by means

of a pin 55 fitted into the head of said piston at approximately the central portion thereof. The opposite end of said connecting rod 18 is inclined downwardly and is formed as a bearing portion or journal 20 which encompasses a circular but eccentrically arranged portion 19 at the lower end of the spindle 4.

Thus, it will be apparent that the horizontal center line of the dashpot cylinder and the eccentric portion 19, respectively, are lying in different planes, i.e., that due to the fact that the elongated intermediate portion of the connecting element 18 is inclined relative to the axis about which the spindle 4 rotates, the end of the element 18 which is attached to the piston 17 lies in a plane that is normal to this axis, which last-mentioned plane is spaced a substantial distance from the other end of the element, namely, the end which is formed as the bearing portion 20 that encompasses the eccentric portion 19 of the spindle 4. As a result of this arrangement, the height of the door closing mechanism is substantially decreased without increasing the side dimension necessary for the braking mechanism. This holds true irrespective of whether hydraulic or mechanical means are employed for the dashpot mechanism as the pressure means is controlled in response to the rotation of the spindle 4. Thus, in accordance with the invention, it is possible to displace the horizontal center plane of the piston 17 and dashpot cylinder 16 a distance corresponding to the height the connecting rod 18 is upwardly inclined, whereby the structural height of the device is decreased by at least one-half the diameter of the cylinder 16, without impairing the function of the structure. Since the dashpot cylinder has always been provided laterally of the spring housing, no increase in the diameter of the external housing is necessary.

It will also be noted that the spring casing 1 is so formed that the chamber within which the spring 9 is received is very deep, so that at least part of the damping cylinder 16 lies in a plane which is normal to the axis of the spindle 4 and which passes through the spring 9.

The piston 17 is provided with a check valve mechanism 56 of conventional design permitting influx of a hydraulic medium into the dashpot cylinder 16 to cushion the return movement of the door. In addition, fluid bypass passageways 57 and a control valve 58 are provided which are conventional in the art and, therefore, need not be described. The control valve 58 regulates the rate of efflux of the fluid medium by means of the bypass to ensure effective braking of the door.

The wall of the spring casing 1 is cut away at its rear and front portions to define abutments 21 against which the outer end 22 of the spiral spring 9 is bearing during rotation thereof, said spring being held together by means of a steel clip or band 23. The internal housing is disposed within the external housing 24 and provided with a cover or lid 25 serving to close the rear face of this external housing. As a result of the upward displacement of the dashpot cylinder 16, the left flange 14 adjacent this dashpot cylinder 16 had to be narrowed in height and, therefore, is made so wide that it can receive two mounting bores 26 arranged adjacent one another. As the dashpot is only on the left side of the mechanism, see FIGURE 1, the right flange 15 can be provided with two mounting bores 26 arranged underneath one another. It will be apparent that, according to the present invention, a space saving and compact arrangement is obtained which is especially well suited for use with metal doors having narrow door frames. As a result thereof, intermediate members, usually employed for mounting conventional door closers, can be omitted.

FIGURES 5 to 7 of the drawings show a mounting plate 27 to which is secured the inventive door-closing assembly by means of mounting members 28. The mounting plate 27 is attached to a metal frame 32 of a

door by means of fastening bolts 29 extending through suitable apertures 30 provided in the mounting plate 27 and through spacer elements 31. Brackets or flap members 33 are cut into and flexed at approximately right angles to the mounting plate 27 and spaced above and below the mounting member 28. Each top flap 33 is provided with a threaded aperture 35, whereas each lower flap has a plain bore 34 aligned with said threaded aperture 35. In assembling the device, the mounting members 28 are inserted between the flexed brackets 33. As a result of this arrangement, the door closer will be suspended between said brackets 33, so that a mechanic, during installation of the device, has his hands free to perform other functions and, moreover, is not required to support the weight of the door-closer during assembly thereof. The mounting members 28 are provided with a bore 36 which is axially aligned with the holes 34 and 35 provided in the brackets 33. Bolts 37 insertable from below mount the door closer casing on the mounting plate 27, these bolts 37 passing through the openings 34 and bores 36 and engage the threaded bore 35 whereby upon tightening of the bolts 37, the mounting members 28 are held between the flexed brackets 33.

A primary advantage of the novel mounting resides in the possibility of assembling the unit in the shop and of mounting the door closer by a single person. The rear of the mounting plate 27 may be designed so that it can be either partially or entirely inserted in the groove of the metal door frame.

A plurality of flaps 38 are cut from the longitudinal sides of the mounting plate 27 and are bent outwardly at a slight inclination, i.e., about 30°. The cup-shaped external housing 24 is provided on its inner walls, adjacent its edges, with stop elements or protrusions 39 adapted to grip over the outer edges of the flaps 38 to ensure that the housing 24 will be securely held onto the mounting plate 27.

According to FIGURE 8, the mounting plate 27 is provided on its edges with flanges 59 which are forwardly bent portions of this plate and are adapted to hold thereon the housing 24 with a press fit.

It is possible to make the mounting plate 27 of thinner sheet material and to secure thereto separate angle members serving as flaps 33. These angle members may then be provided with bores adapted to receive bolts serving as supporting means for both the door closing assembly and the mounting plate.

In accordance with FIGURES 7 and 9, the outer housing 24 is provided with a cutout 40 in the zone of the pivot axis of the connecting lever 11, said cutout permitting assembly of the outer housing 24 to the mounting plate 27. The provision of this cutout 40, extending to the mounting plate 27, however, makes it possible for dust and other foreign matter to penetrate the housing 24. To overcome this disadvantage, a cover sheet 41 is provided around the spindle 4 between the spring casing 1 and the ratchet wheel 6. The outer housing is then placed over this cover sheet 41 to obtain a tight door closer assembly. The cover sheet or plate 41 is provided with a lug 42 which abuts one face of the mounting plate 27 to tightly close the cutout 40 when the housing 24 is assembled thereover. In order to prevent turning of the cover sheet 41, a boss or protuberance 43 is provided on the lug 42, so that the edge of said boss 43 bears against the edge 44 of the cutout 40. The housing 24 has a smooth outer surface which can be easily cleaned.

The operation of the door closing mechanism is as follows: Initially, the ratchet wheel 6 is rotated to a desired position and the detent 12 is gravitated into one of the peripheral slots 13 in order to pre-tension the spiral spring 9. Upon opening of the door, the lever 11 rotates the spindle 4 and the ratchet wheel 6, the latter tensioning the spring 9 to store elastic energy for closing the door. The rotation of the spindle 4 causes displacement of the piston 17 to the right and, simultaneously, causes admittance

tance of a fluid medium through the check valve 56 into the dashpot cylinder. During closing of the door, the spring 9 releases its stored energy and the fluid medium is bypassed and returned to the hydraulic system, acting as a cushion for the door, so as not to slam shut unduly rapidly. It will, thus, be apparent that the instant invention encompasses a novel door closing mechanism which is reliable in its operation and more compact than the devices of this kind heretofore known.

We claim:

1. In a door closer, the combination which comprises: a housing; a spindle mounted in said housing for rotation about an axis, said spindle having near one end an eccentric portion; spring means encompassing said spindle; and damping means arranged in said housing, said damping means comprising a cylinder at least part of which lies in a plane which is normal to said axis and which passes through said spring means and the axis of which cylinder intersects said spindle axis at a point between said eccentric portion and the other end of said spindle, said damping means further comprising a piston slidably arranged in said cylinder and a connecting element one end of which is attached to said piston at approximately the central portion thereof and the other end of which element is formed as a bearing portion and encompasses said eccentric portion of said spindle, said element having an elongated intermediate portion which is inclined relative to said spindle axis so that said one end of said element which is attached to said piston lies in a plane normal to said spindle axis which last-mentioned plane is spaced a substantial distance from said other end of said element which is formed as said bearing portion and encompasses said eccentric portion of said spindle.

2. The combination defined in claim 1, further comprising wall means encompassing said spindle and forming an annular chamber within which said spring means are arranged, said eccentric portion of said spindle being arranged immediately below the bottom of said chamber.

3. The combination defined in claim 2, wherein said wall means are formed with a plurality of radial cutouts which divide said wall means into a plurality of wall portions.
5. The combination defined in claim 3, wherein said spring means are spiral and have an outer end portion hooked to an edge of one of said wall portions, whereby said spring means may be so hooked as to impart clockwise or counter-clockwise rotation to said spindle.
10. The combination defined in claim 1 wherein said housing comprises a cap-like member and a mounting plate serving to mount said housing onto a support and covering the opening of said cap-like member, thereby enclosing the other components of the door closer.
15. The combination defined in claim 5, wherein said mounting plate is provided with a plurality of inwardly bent ear portions, wherein said housing has at least one mounting member adapted to fit between two of said inwardly bent ear portions of said mounting plate, and wherein said mounting member and said ear portions are joined together by a releasable bolt member extending in a direction generally parallel to said spindle axis.
20. The combination defined in claim 5, wherein said cap-like member is provided with a cut-out through which said other end of said spindle projects, and wherein there is provided a cover sheet for covering said cutout.
